UNITED STATES PATENT OFFICE.

ROBERT A. TRIBBLE, OF ROLLING FORK, MISSISSIPPI.

VENDING APPARATUS.

1,305,033.

Specification of Letters Patent. Patented May 27, 1919.

Application filed March 5, 1919. Serial No. 280,745.

To all whom it may concern:

Be it known that I, ROBERT A. TRIBBLE, a citizen of the United States, residing at Rolling Fork, in the county of Sharkey 5 and State of Mississippi, have invented certain new and useful Improvements in Vending Apparatus, of which the following is a specification.

This invention relates to a vending apparatus and more particularly to an apparatus of the self-serving variety wherein a customer is permitted to help himself from a displayed stock of goods. It is desirable in apparatus of this nature to have 10 the various structures embodying the same disposed in such manner as to display to each and every customer substantially the entire stock of goods; to keep the body of purchasers moving substantially continuously 15 in the same direction in order to avoid confusion and congestion; to utilize all available space to the best advantage subject to the accomplishment of the foregoing objects and finally to cause each purchaser 20 to pass a common point at which the goods selected may be checked up and collected 25 for.

Further objects and advantages of the invention will be set forth in the detailed description which now follows.

In the accompanying drawings—

Figure 1 is a diagrammatic sectional view of a store-room having vending apparatus disposed therein in a novel manner and in 35 accordance with the invention;

Fig. 2 is a like view of a modified form of the invention;

Fig. 3 is a like view of a further modification of the invention; and

Fig. 4 is a like view of still another modification of the invention.

Referring particularly to Fig. 1, 5 designates the outer walls of a storeroom which may be what I have termed a "grocereteria," 45 i. e. a grocery store in which groceries of all kinds are so displayed that customers may help themselves to the same. It is manifest that stores of this nature possess many advantages among which may be mentioned 50 the marked decrease in expense arising from the fact that it is not necessary to employ clerks to wait upon customers, that the customer has an opportunity to inspect the entire stock and will consequently make 55 many purchases that he or she would not otherwise make and that the customer is not

forced to select goods hastily under pressure of the knowledge that other persons are waiting for the attention of a clerk. In carrying out the invention I provide an entrance 6 which may, if desired, be located within a vestibule or lobby 7. The entrance 6 is preferably controlled by a turnstile or storm door 8 of such construction as to permit the passage of customers in one direction 60 only into the interior of the store. The store is divided longitudinally for a portion of its depth by a partition 9 which may extend to the ceiling but is preferably in the form of a picket fence to permit customers 65 to have a clear view from one side of the store to the other. A display stand 10 may, if desired, be located in the length of this partition. Lying transversely across the inner end of the partition 9 is a display shelf 11 that is divided longitudinally by a wall 12. A customer passing into the store through the entrance 6 and in the direction indicated by the arrow A finds goods displayed upon shelves 13, upon the display stand 10 and upon shelves or stands 14, though these latter may be omitted if desired. The shelf 11 is preferably 70 of arcuate form and lies in spaced relation to a similarly shaped shelf 15 formed along 75 the front wall of a storeroom 16 from which the several shelves and stands may be replenished at suitable intervals. The arcuate formation of the shelf 11 and the similar formation of the shelf 15 and 80 their relation to each other constitute an arcuate passageway 17 curved in such manner as to direct the travel of the customers easily and without confusion thereto and to guide this travel to the opposite side of 85 the store where, following the direction of the arrow B, the customer finds his way toward the exit 18 which is controlled by a turnstile or storm door similar to that described with respect to the entrance but arranged to prevent the passage of persons inwardly and to permit the passage of persons outwardly.

In their travel toward the exit the customers are directed toward a cashier's cage 105 19 where the cost of the goods that have been selected may be computed and the charge for the same paid.

The storeroom is provided with doors 20 leading from the rear of the building and 110 with doors 21 through which communication may be had between the storeroom and

the interior of the store proper. Under normal conditions the doors 20 serve to permit goods to be unloaded from teams into the storeroom 16 and the doors 21 permit these goods to be conveyed from the storeroom to replenish the shelves and stands in the store. Ordinarily customers will not be permitted to pass through these doors but in case of fire these doors provide emergency exits. Additional emergency exits may be provided by doors 22 which will normally be kept closed but not locked so that in case of fire passage may be had to the lobby other than through the turnstiles.

15 The structure illustrated in Fig. 2 is similar to that illustrated in Fig. 1 and in so far as the two forms of the invention are identical the same reference characters have been applied. In this form, however, the longitudinal partition 9^a instead of lying centrally of the store, extends from the front of the store to one end of the shelf 11 and additional arcuate shelves 11^a and 11^b are employed. A division wall or fence 9^b extends from the cashier's cage 19 to the shelf 11^b and preferably comprises within its length a circular display stand 10^a. I also preferably employ a division wall or fence 9^c which extends from one end of the shelf 11^a to the side wall of the store so that the travel of the customers will be in the direction of the arrows C, D, E and F.

In the form of the invention illustrated in Fig. 3 an entrance is provided at 23 within 35 in a lobby 24 and the store room is partially longitudinally divided by an oval shelf 25 within which a space 26 is provided for the reception of employees. This structure is advantageous where it is desired to 40 provide a central wrapping station to which customers may bring their purchases and have them checked and wrapped, where necessary, before passing the cashier's station indicated at 27. The exit in this case 45 is at 28 into a lobby 29 and the respective exits and entrances 30 and 31 to the lobbies 28 and 29 may be controlled by storm doors or turnstiles 32 and 33.

In Fig. 4 of the drawings I have illustrated a construction wherein a longitudinal partition 9^e is disposed within the store and carries display shelves upon its opposite sides, indicated at 34, and in addition carries a shelf 35 upon which customers may 50 place their baskets and move them along as they travel down the one side of the store and up the other. These shelves are curved around the inner end of the partition to conform to the general curvature of the passageway 17^a formed between said shelves and the shelves 15^a which correspond to the shelves 15 in Fig. 1, this arrangement serving the purpose of aiding in keeping the movement of purchasers always in one direction and changing the direction of move-

ment at the rear of the store from rearward to forward with the least possible confusion.

Show windows 36 are indicated in Fig. 4 and the entrance and exit are indicated at 37 and 38 respectively and are preferably controlled by turnstiles 38' and 39 serving the function hereinbefore set forth. It is to be noted that the structure illustrated in Fig. 4 is particularly adapted to buildings that are long and narrow and also lends itself admirably to the utilization of two stores next door to each other, in which case it is only necessary to cut away a part of the division wall between the two buildings to form the passageway 17^a and to build 75 the storeroom across the back of the two buildings. The cashier's cage 19^a may in this case be located as shown or may lie entirely within the exit side of the store.

From the foregoing description it will be 85 seen that the described arrangement provides vending apparatus by which customers may serve themselves, expensive clerk hire may be dispensed with, ample opportunity may be given the customer to make his or 90 her selections, all of the goods within the store will be brought within the range of vision of each and every customer during his or her passage therethrough, the customers will be encouraged to make larger purchases upon each visit, overhead expenses in many respects will be diminished, possibilities of mistakes will be eliminated and the many losses incident to the conduct of 95 a business wherein a large number of clerks 100 are required to add up amounts due from customers, often in great haste, will be avoided.

While I have chosen to describe the application of the invention in connection with 105 a grocery it is manifest that goods of many kinds may be dispensed in the same way, the primary object being to provide a structure of the character indicated in which the several objects are achieved in the most simple, 110 economical and advantageous manner. It is therefore to be understood that the invention is not limited to the precise construction set forth but that it includes within its purview whatever changes fairly come within the scope or the spirit of the appended 115 claims.

Having described my invention, what I claim is:

1. A vending structure of the character 12 described comprising a storeroom having an entrance and an exit and a longitudinally extending partition therein between the entrance and the exit and extending for a major part of the depth of said storeroom 12 and means located at the inner end of the partition and transversely with respect thereto constituting a laterally extending arcuate passageway, the concaved side of which lies toward the partition and non- 130

reversible entrance and exit structures upon opposite sides of the partition requiring traffic to enter upon one side of the partition and leave upon the other side thereof, 5 the curvature of the lateral passageway being in the general direction of travel of the traffic.

2. A vending structure of the character described having an entrance and an exit 10 and a longitudinally extending partition between the entrance and the exit, of means at the entrance and exit for requiring traffic to enter at one side of the partition and

leave at the other side thereof, the rear wall of the storeroom being of arcuate formation 15 with its concaved side toward the partition and an arcuate shelf disposed transversely across the end of the partition with its convex side disposed toward said arcuate wall, to thereby constitute a laterally extending 20 arcuate passageway disposed in the general direction of travel from the entrance to the exit.

In testimony whereof I affix my signature.

ROBERT A. TRIBBLE.
